E. EDWIN.
ELECTRIC ARC FURNACE,
APPLICATION FILED MAY 13, 1915.

Patented Aug. 8, 1916.

Inventor
Emil Edwin
Henry Orth

UNITED STATES PATENT OFFICE.

EMIL EDWIN, OF CHRISTIANIA, NORWAY, ASSIGNOR TO NORSK HYDRO-ELEKTRISK
KVAELSTOFAKTIESELSKAB, OF CHRISTIANIA, NORWAY.

ELECTRIC-ARC FURNACE.

1,193,882.

Specification of Letters Patent. Patented Aug. 8, 1916.

Application filed May 13, 1915. Serial No. 27,830.

To all whom it may concern:

Be it known that I, EMIL EDWIN, a subject of the King of Norway, residing at Christiania, Norway, have invented certain new and useful Improvements in Electric-Arc Furnaces; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification.

15 The present invention relates to electric arc furnaces with long stable arcs and particularly to tube furnaces, in which the arc is burning between an insulated inner electrode and an outer electrode, which also may 20 serve as a cooler.

It is known, that the long stable arcs in electric furnaces of the Schönherr type are generally maintained between an insulated electrode and a cooled tube, which is electrically connected directly to the flame tube and the outer parts of the furnace. Owing to this arrangement it has previously been considered necessary to connect the said cooler as well as flame tube to earth.

30 According to this invention the electrode and flame tube have not a constant potential, which would be the case were the said parts grounded, so that the potential of these two members may vary in accordance with the 35 electrical conditions of the system and as compared to the potential of the earth. Said electrode as well as the flame tube, are arranged so that they can adjust themselves automatically to a potential corresponding 40 to the forces acting on the furnace system and its connections. The importance of this arrangement is particularly apparent when a number of star-connected furnaces are connected in parallel on a large source of

45 power. In the latter case the said arrangement adds materially to the stability of the flame, and as increased stability in most cases means increased chemical efficiency, the said arrangement brings with it a very 50 great advantage.

The practical embodiment of the invention is illustrated diagrammatically on the accompanying drawing.

A, B, C represent three electric flame tube furnaces of the type referred to. Said

furnaces are provided with insulated electrodes D, which are connected to the phases E, F, G of a three-phase system. The electric flame is maintained between said electrodes and the interior wall of the coolers 60 H, which form the opposite end of the tube furnace. Said coolers are electrically connected with their respective furnaces and with each other, as indicated by lines I. The furnace tubes and the coolers are however not connected to earth but are insulated from the same as well as from any object connected to earth or otherwise liable to prevent the free automatical adjustment of the potential of the star point. The 70 effect of this arrangement will be understood with reference to the following analogy: If a number of elastic rubber strings are connected so as to form a star figure, and the free ends of the strings each are 75 exposed to varying stresses which strain the same up to their elastic limit, the several strings will be far more liable to break, if the star center is kept stationary, than if the same is allowed to move freely according 80 to the combined stress transmitted to the same by the strings. In the analogy the strings correspond to the electric arcs, which also have a certain elastic limit, and the connecting point of the star corresponds 85 to the star point of an electric star connection. The varying mechanical stresses correspond to the varying electrical forces created in the flame owing to irregularities in the flow of air around the same. If now, as it has previously been done, the star point is made stationary by being connected to earth, the several arcs will be liable to break and extinguish (bad stability). If 90 however according to the present invention the star point is allowed to adjust itself 95 freely in the field of potential, the arcs will be less liable to break and their stability will be increased accordingly.

What I claim is:

1. In a system comprising a plurality of electric arc furnaces, a tube forming the reaction chamber of each furnace, an electrode insulated from the tube at one end and an electrode electrically connected with the tube at the other end, a gas inlet near the said insulated electrode and a gas outlet near the other electrode, an electrical connection to a source of electricity from each of the said insulated electrodes and an elec- 110

trical connection insulated from earth between the other electrodes.

2. In a system comprising a plurality of electric arc furnaces, a tube forming the reaction chamber of each furnace, an electrode insulated from the tube at one end and an electrode electrically connected with the tube at the other end, a gas inlet near the said insulated electrode and a gas outlet near the other electrode, a polyphase source of electricity, an electrical star connection between the said insulated electrodes belonging to a group of the furnaces and the corresponding phase of the source of electricity, groups of furnaces being connected in parallel with said source of electricity, and an electrical connection insulated from earth between the other electrodes.

3. In a system comprising a plurality of electric arc furnaces, a tube forming the reaction chamber of each furnace, an electrode insulated from the tube at one end

and an electrode electrically connected with the tube at the other end, a gas inlet near the said insulated electrode and a gas outlet near the other electrode, a polyphase source of electricity, an electrical star connection between the said insulated electrodes belonging to a group of the furnaces and the corresponding phase of the source of electricity, groups of furnaces being connected in parallel with said source of electricity, and an electrical connection insulated from earth between the other electrodes.

In testimony that I claim the foregoing as my invention, I have signed my name in presence of two subscribing witnesses.

EMIL EDWIN.
